PRIME MOVER

Fay A. Farrar, San Jose, Calif.

Application October 30, 1942, Serial No. 463,967

2 Claims. (Cl. 253—56)

This invention relates to an improved prime mover or compressed air motor adapted to do useful work such as propelling vehicles, airships, projectiles, and the like.

Stated more specifically, the preferred embodiment of the invention is more in the nature of a rotary air motor of such consolidated and structurally concentrated form as will function to provide a powerful source of manually and mechanically regulated power as may be needed for various propulsion purposes.

In reducing to practice the preferred embodiment of the inventive concept, I have adopted for use a shaft propelling rotor, said rotor embodying a multiplicity of abutments and coaxial air projecting nozzles, said nozzles being connected with a compressed air chamber and having associated therewith conveniently and reliably operable valving means, whereby to provide a structural assemblage aptly fitted to accomplish the desired aims and purposes.

Another object is the provision of a relatively simple and economical compressed air motor characterized by strength and durability and capable of producing a source of powerful energy making it possible for a comparatively small apparatus to perform heavy duty results.

Other features and advantages will become more readily apparent from the following description and the accompanying illustrative drawings.

In the drawings, wherein like numerals are employed to designate like parts throughout the views:

Figure 1 is a longitudinal view on the line 1—1 of Figure 2 through the compressed air motor constructed in accordance with the principles of the present invention, part appearing in section and elevation to depict the essential structural parts thereof.

Figure 2 is a transverse or cross-sectional view of the structure seen in Figure 1, the section being on the line 2—2 of Figure 1.

Figure 3 is a fragmentary detail sectional view of one of the air delivery nozzles and the associated valving means therefor.

Figure 4 is an enlarged fragmentary longitudinal sectional view through one of the valve guides showing the slidable valve plate therein.

Figure 5 is a perspective view of the slidable or reciprocatory valve plate.

Figure 6 is a detail sectional and elevational view of the header ring on which the valve plates are mounted for simultaneous actuation.

Figure 7 is a detail view of the operating yoke for said header ring, or annulus.

Referring now to the drawings by distinguishing reference numerals, it will be seen that the main or body portion of the structure is essentially characterized by an inner horizontal cylinder 9 surrounded by a spaced parallel outer cylinder 10. The intervening space between said parts 9 and 10 constitutes a compressed air receiving and storing chamber 11. This main structure is supported on an appropriate base 12, as shown to advantage in Figures 1 and 2. The numeral 13 designates a pipe attached at a suitable point to the outer shell or cylinder 10 which is adapted to supply compressed air of predetermined capacity to the chamber 11. In practice this pipe 13 is connected with an air compressor (not shown) and appropriate valving means, preferably automatic, is generally used to let air into the chamber 11 when the pressure therein is reduced, by use, to a predetermined low state. The numeral 14 designates an appropriate pressure blow-off or relief valve. As brought out to advantage in Figure 3, the inner cylindrical shell or rotor housing 9 is provided on its interior with a multiplicity of angularly canted tapered tubes 15 hereinafter referred to as nozzles. The outer ends of these nozzles register with ports 16 in the embossed or raised valve guide 17. In this valve guide there is a slidable valve plate 18 having apertures 19 to register with the ports and intake ends of the respective nozzles 15. Observing the nozzle assembly, it will be noted that each annular row comprises circumferentially spaced nozzles. And there are any number of annular rows of nozzles extending the full length of the rotor housing 9, as brought out to advantage in Figures 1 and 2. There are also valve guides and slide valves arranged to correspond with the sets or rows of nozzles for effective air regulation and control. In addition, and between the two housings 9 and 10, I provide equidistant, circumferentially spaced, longitudinally elongated exhaust ducts 20. These serve to deliver the exhausted or used air from the rotor housing 9 to the disposal exhaust manifold 21 mounted on the exterior of the outer shell or housing 10. This provides for equalized exhausting of used air and disposal thereof to the outside atmosphere. The manifolds 21 have suitable connections through the necks 22 to the respective or adjacent exhaust ducts 20.

The disk-like end plates 23 and 24 serve to close the opposite ends of said housing 9. These plates 55 are provided with appropriate bearings 25 and 26

to accommodate the shafts at the opposite ends of the multiple pocketed rotor or impeller 21. The shaft 28 may be denoted as the power take-off shaft, this to be connected with the device adapted to be driven from said rotary impeller. This rotor is made up of a plurality of longitudinally spaced disks 29 with radial, circumferentially spaced abutments 30 therebetween. The abutments and intervening pockets 31 are adapted to receive the pressured air jets from the coating nozzles in an obvious manner. Operation of the valves 13, of course, is such as to be able to cut off the air or regulate the intensity of flow from the chamber 11 into the rotor housing, as is obvious. The valve assembly includes an annulus or push-pull ring 32 with which the outer ends of the valves connect, as indicated at 33 and 34, in Figure 4. In addition, there is an operating yoke 35, which yoke is connected to diametrically opposite points of the ring, said yoke being in turn actuated by a control lever 36 pivotally mounted on an adapter bracket 37.

In practice, and as perhaps apparent from the drawings and description so far covered, the motive force is air pressure, and this comes from an appropriate air compressor which delivers the air through the pipe 13 into the receiving and storage chamber 11. When the valves 13 are adjusted to open the ports 16, the air rushes into the chamber surrounded by the rotor casing 9, finding its way through the medium of the concentrating nozzles 15. The air emitted under pressure from these nozzles impinges on the impeller blades or abutments 30. Thus, the rotor, as a unit, is set into motion to drive the power take-off shaft 28. Excessive air pressure is taken care of by way of the automatic relief valve 14. The exhaust is taken care of by way of the circumferentially spaced ducts 29 communicating with the external disposal manifolds 21. And, as is obvious, the lever 36 serves to actuate the ring 32 and the ring serves to operate the valves simultaneously.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and

rearrangement of parts may be resorted to in actual practice so long as no departure is made from the invention as claimed.

What I claim is:

- 5 1. In an air motor of the class described, an outer cylindrical shell constituting a housing and provided with a relief valve and a compressed air supply pipe, an inner concentric cylindrical housing, the housings being joined at their outer ends, longitudinally extending circumferentially spaced equidistant exhaust ducts connecting said housings together, exhaust disposal manifolds surrounding the outer housing and having communicating connection with said ducts, said inner housing being provided on its exterior with longitudinally extending valve guides, valves slidable in said guides, said inner housing being further provided with a multiplicity of internal angularly disposed air delivery nozzles, and a rotor mounted for rotation in said inner housing, said rotor including a multiplicity of radial abutments carried by adjoining disks, said abutments and disks defining V-shaped pockets and said nozzles being in alignment with said pockets in the manner and for the purposes described.
- 10 2. In an air motor of the class described, an outer cylindrical shell constituting a housing and provided with a relief valve and a compressed air supply pipe, an inner concentric cylindrical housing, the housings being joined at their outer ends, longitudinally extending, circumferentially spaced, equidistant exhaust ducts connecting said housings together, exhaust disposal manifolds surrounding the outer housing and having communicating connection with said ducts, said inner housing being provided on its exterior with longitudinally extending valve guides, valves slidable in said guides, said inner housing being further provided with a multiplicity of internal angularly disposed air delivery nozzles, and a rotor mounted for rotation in said inner housing, said rotor including a multiplicity of radial abutments carried by adjoining disks, said abutments and disks defining V-shaped pockets and said nozzles being in alignment with said pockets in the manner and for the purposes described.
- 15 3. In an air motor of the class described, an outer cylindrical shell constituting a housing and provided with a relief valve and a compressed air supply pipe, an inner concentric cylindrical housing, the housings being joined at their outer ends, longitudinally extending valve guides, valves slidable in said guides, said inner housing being further provided with a multiplicity of internal angularly disposed air delivery nozzles, and a rotor mounted for rotation in said inner housing, said rotor including a multiplicity of radial abutments carried by adjoining disks, said abutments and disks defining V-shaped pockets and said nozzles being in alignment with said pockets in the manner and for the purposes described.
- 20 4. In an air motor of the class described, an outer cylindrical shell constituting a housing and provided with a relief valve and a compressed air supply pipe, an inner concentric cylindrical housing, the housings being joined at their outer ends, longitudinally extending, circumferentially spaced, equidistant exhaust ducts connecting said housings together, exhaust disposal manifolds surrounding the outer housing and having communicating connection with said ducts, said inner housing being provided on its exterior with longitudinally extending valve guides, valves slidable in said guides, said inner housing being further provided with a multiplicity of internal angularly disposed air delivery nozzles, and a rotor mounted for rotation in said inner housing, said rotor including a multiplicity of radial abutments carried by adjoining disks, said abutments and disks defining V-shaped pockets and said nozzles being in alignment with said pockets in the manner and for the purposes described.
- 25 5. In an air motor of the class described, an outer cylindrical shell constituting a housing and provided with a relief valve and a compressed air supply pipe, an inner concentric cylindrical housing, the housings being joined at their outer ends, longitudinally extending valve guides, valves slidable in said guides, said inner housing being further provided with a multiplicity of internal angularly disposed air delivery nozzles, and a rotor mounted for rotation in said inner housing, said rotor including a multiplicity of radial abutments carried by adjoining disks, said abutments and disks defining V-shaped pockets and said nozzles being in alignment with said pockets in the manner and for the purposes described, together with a single shifter ring, the valves being connected at their outer ends to said ring, a yoke attached to said ring for operating the same, and a lever for operating the yoke as described.

FAY A. FARRAR.
